Leo R. Sauer, by
G. Kennedy,
Attorney.

UNITED STATES PATENT OFFICE.

LEO R. SAUER, OF WATERLOO, IOWA.

DESIGN FOR A LAMP-CASING.

56,946.

Specification for Design.

Patented Jan. 18, 1921.

Application filed August 16, 1920. Serial No. 403,944. Term of patent 14 years.

To all whom it may concern:

Be it known that I, LEO R. SAUER, a citizen of the United States of America, and a resident of Waterloo, Blackhawk county, Iowa, have invented a new, original, and ornamental Design for a Lamp-Casing, of which the following is a specification, reference being had to the accompanying drawing, forming part thereof.

Figure 1 is an elevation of a lamp-casing, showing my new design, and Fig. 2 is a perspective view thereof.

I claim:

The ornamental design for a lamp-casing, as shown.

Signed at Waterloo, Iowa, this 2d day of August, 1920.

LEO R. SAUER.
